United States Patent Office

Des. 226,395

Patented Feb. 27, 1973

SUBSTITUTE FOR MISSING XR

226,395

FRESNEL LENS

William H. Dorman, Corning, N.Y., assignor to Corning
Glass Works, Corning, N.Y.

Filed May 24, 1971, Ser. No. 146,582

Term of patent 14 years

Int. Cl. D26—05, 06

U.S. Cl. D48—16 A

Fig. 1

Fig. 2

Fig. 3

FIG. 1 is a top plan view of a Fresnel lens showing my new design.

FIG. 2 is an enlarged sectional view taken on line 2—2 of FIG. 1.

FIG. 3 is an enlarged fragmentary top plan view of the center of the lens.

I claim:

The ornamental design for a Fresnel lens, as shown.
